CLAIM

The ornamental design for a case, as shown and described.

DESCRIPTION

FIG. 1 is a perspective view showing my new design;

FIG. 2 is a top plan view thereof;

FIG. 3 is a rear elevational view thereof;

FIG. 4 is a side elevational view thereof; and,

FIG. 5 is a bottom plan view thereof.

The case is shown with a symbolic break in its height, represented by jagged lines. The appearance of any portion of the article between the jagged lines forms no part of the claimed design.
